Specification for Design.

Patented Oct. 4, 1921.

Application filed February 19, 1921. Serial No. 446,525. Term of patent 3½ years.

To all whom it may concern:

Be it known that I, HERMAN D. STEEL, a citizen of the United States, and a resident of Philadelphia, county of Philadelphia, and State of Pennsylvania, have invented a certain new, original, and ornamental Design for Precious, Semiprecious, or Synthetic Jewels, as shown in the accompanying drawings, in which—

Figure 1 is a top plan view of a jewel (unset) embodying the new design;

Fig. 2 is a side elevation; and

Fig. 3 is a bottom plan view of the same.

I claim:—

The ornamental design for a precious, semi-precious, or synthetic jewel, substantially as shown.

In witness whereof I have hereunto set my hand this 17th day of February, A. D. 1921.

HERMAN D. STEEL.
